CLAIM

The ornamental design for a lighting system, as shown and described.

DESCRIPTION

FIG. 1 is a front isometric view of a lighting system;
FIG. 2 is a front view of the lighting system;
FIG. 3 is a rear view of the lighting system;
FIG. 4 is a top view of the lighting system;
FIG. 5 is a bottom view of the lighting system;
FIG. 6 is a first end view of the lighting system;
FIG. 7 is a second end view of the lighting system;
FIG. 8 is a front isometric view of another embodiment of the lighting system of FIG. 1 showing two lenses;
FIG. 9 is a front view of the lighting system shown in FIG. 8;
FIG. 10 is a rear view of the lighting system shown in FIG. 8;
FIG. 11 is a top view of the lighting system shown in FIG. 8;
FIG. 12 is a bottom view of the lighting system shown in FIG. 8;
FIG. 13 is a first end view of the lighting system shown in FIG. 8; and,
FIG. 14 is a second end view of the lighting system shown in FIG. 8.
The portions shown in broken lines are included to show environment and form no part of the claimed design.
